UNITED STATES PATENT OFFICE.

JOHN F. KISSANE AND FRANK E. SCHOONMAKER, OF DETROIT, MICHIGAN.

DOOR-LOCKING MECHANISM.

1,306,260.

Specification of Letters Patent. Patented June 10, 1919.

Application filed April 11, 1918. Serial No. 228,011.

To all whom it may concern:

Be it known that we, JOHN F. KISSANE and FRANK E. SCHOONMAKER, citizens of the United States of America, residing at De-

troit, in the county of Wayne and State of Michigan, have invented certain new and useful Improvements in Door-Locking Mechanism, of which the following is a specification, reference being had thereto to

10 the accompanying drawings.

This invention relates to door locking mechanism, and more particularly to an automatic electric street car door interlocking device, which will prevent the motorman or

15 operator of a street car from starting a car with any of the doors open.

The primary object of our invention is to provide an interlocking device of the above type which may be advantageously used in

20 connection with any type of street car or other vehicle having doors that may be opened and closed by the motorman or conductor of a street car, the device controlling the electric circuit in connection with the

25 controller of the street car thereby preventing the motorman from starting the car while doors are open, thus eliminating accidents due to passengers standing on door-steps or attempting to enter or leave a car.

30 A further object of our invention is to provide an electrically operated lock for a car door, which is controlled by a motorman of a car, thus preventing a conductor, passengers or persons outside of the car from

35 opening the door while the car is in motion.

The above and other objects are attained by a novel arrangement of parts that are hereinafter described and then claimed, and reference will now be had to the drawings,

40 wherein

Figure 1 is a longitudinal horizontal sectional view of a car body, illustrating diagrammatically the electrical devices associated with the doors of the car body and in

45 circuit with the controller of the car;

Fig. 2 is a horizontal sectional view of a portion of a car, showing what is ordinarily termed a "rat-trap" door, and

Fig. 3 is a perspective view of the same,

50 showing an electric lock for the door.

In describing our invention by aid of the views above referred to, we desire to point out that the same are merely illustrative of an example by which our invention may be

55 put into practice, since there are various types of cars, doors, and door operating

mechanisms. It is therefore to be understood that our invention is susceptible to such changes as fall within the scope of the appended claims.

In the drawings, the reference numeral 1 denotes the body of a street car or other vehicle having doors 2 of a "rat-trap" type, that is, each door is composed of two sections hinged together with one of the sections hinged to the car body, so that when the door is opened, the sections thereof are swung into parallelism.

Associated with the doors 2 are door operating mechanisms 3, which may include 70 rock shafts, cranks, toggle levers, reach rods, and such other members that will permit of the conductor or motorman of the car opening and closing the doors at a point remote therefrom.

Adjacent the door operating mechanism we locate a stationary switch member 4 and we connect to some part of the door operating mechanism, a movable switch member 5 which may be shifted by the door operating mechanism 3 to and from the stationary switch member 4. The switch members 4 and 5 may be in the form of a knife, lever or other form of switch that will open and close an electric circuit. Diagrammatically 85 we have illustrated the switch as a lever switch with all of the switches connected by wires 6 to the controller 7 of the car, so that the car cannot be set in motion by the motorman until all of the switches are closed. 90 This is only accomplished by having the doors closed, and if the doors 2 are not completely closed, then the switches are open and there is broken circuit at the controller 7, that prevents operation of the car. 95

Adjacent each door is an electric locking device in circuit with the controller 7, so that while the car is in motion the doors cannot be opened. Each electric device comprises a solenoid 8, contiguous to a doorway 100 as shown in Figs. 2 and 3, and the core of the solenoid is connected to a locking lever 9 having an end 10 adapted to engage in a keeper 11 in or on the upper edge of the door. The lever 9 is fulcrumed or pivoted 105 on a suitable bracket or bearing 12, carried by the car body, and the end of said lever is connected by a coiled retractile spring 13 to a bracket 14 carried by the car body. The retractile force of the spring 13 is adapted to 110 move the end of the lever 9 out of the keeper 11 when the solenoid 8 is deenergized, such

deenergization taking place when the operating circuit of the car is broken at the controller 7.

From the foregoing, it will be observed that it is necessary for the motorman of the street car to bring the car to a stop before the conductor or even the motorman can open the doors 2 of the car, since during the operation of the car the solenoids 8 are energized, thereby causing the levers 9 to hold the doors 2 closed, against opening by either the conductor, motorman, passengers or persons outside of the car. After the car is brought to a standstill, the conductor or motorman may open the doors 2 and in so doing break the electrical circuit through the controller 7 thus rendering it impossible for the motorman of the car to start the same, until the doors are closed.

20 We believe that when the door operated switches and locking devices are installed that the same will prevent many accidents incurred by passengers standing on door steps or attempting to enter or leave a car when the same is in motion.

What we claim is:

1. The combination with an electrically operated car having hinged doors, and a controller for the electric operating circuit of the car, of door locking devices in circuit with said controller and adapted to prevent opening of the car doors when the car is in

motion, each device comprising a solenoid adjacent the upper edge of each door, a pivoted lever having one end thereof serving 35 said solenoid, and a keeper in the upper edge of each door adapted to receive the opposite end of the lever.

2. The combination of an electrically operated street car body having sectional doors 40 with a section of each door hinged to the car body, a controller for the electric operating circuit of the car, a stationary switch member below the hinged section of each door, a switch member operable in unison 45 with the hinged section of each door adapted to engage the stationary switch member, said switch members being in the car operating circuit when said car doors are closed and adapted to break said car operating circuit when said car doors are open, and door locking devices at the upper edges of the doors and including solenoids in circuit with said controller and adapted to prevent opening of the car doors when the car is in motion. 50

In testimony whereof we affix our signatures in the presence of two witnesses.

JOHN F. KISSANE.

FRANK E. SCHOONMAKER.
